UNITED STATES PATENT OFFICE.

CHRISTIAN H. T. HAGELSTEIN, OF BOSTON, MASSACHUSETTS, ASSIGNOR TO THE REECE
BUTTON HOLE MACHINE COMPANY, OF BOSTON, MASSACHUSETTS, A CORPORATION
OF MAINE.

SEWING-MACHINE.

1,326,659.

Specification of Letters Patent. Patented Dec. 30, 1919.

Application filed May 5, 1917. Serial No. 166,594.

To all whom it may concern:

Be it known that I, CHRISTIAN H. T. HAGELSTEIN, a citizen of the United States, residing at Boston, county of Suffolk, State 5 of Massachusetts, have invented an Improvement in Sewing-Machines, of which the following description, in connection with the accompanying drawing, is a specification, like characters on the drawing representing like parts.

This invention relates to sewing machines and particularly to buttonhole sewing machines which are provided with both upper thread-handling mechanism and under 15 thread-handling mechanism, and one of the objects of the invention is to provide a novel mechanism for manipulating the under thread at the end of a stitching operation on a buttonhole so as to draw out from the thread supply a sufficient length of under thread to insure the proper formation of the initial stitch of the next stitching operation and at the same time to cut the thread close 20 to the underside of the work.

25 Another object of the invention is to provide a mechanism of this type which is adapted also to similarly manipulate the filling or stay-cord which is delivered to the edge of the buttonhole from beneath and 30 over which the edge stitches of the buttonhole are formed, and to otherwise improve buttonhole sewing machines, all as more fully hereinafter set forth.

In order to give an understanding of my 35 invention I have illustrated in the drawings a selected embodiment thereof which will now be described, after which the novel features will be pointed out in the appended claims.

40 Figure 1 of the drawings is a side view of a portion of a buttonhole sewing machine showing my improvements applied thereto;

Fig. 2 is a fragmentary front view showing the bed plate and the under thread-handling mechanism;

Fig. 3 is an enlarged side view of the upper portion of the turret which carries the under thread-handling mechanism;

Fig. 4 is a view of the upper part of said turret taken at right angles to Fig. 3;

Fig. 5 is a plan view of the work-holding means, said view showing the mechanism for drawing out and cutting the under thread;

Fig. 6 is a similar view showing the parts 65 in a different position;

Fig. 7 is a sectional view on the line 7—7, Fig. 6;

Fig. 8 is a view of the slide 29 and the pulling-off finger 27.

I will first refer briefly to the principal parts of the buttonhole sewing machine herein illustrated and will then describe in detail my improvements.

The buttonhole sewing machine shown in 65 the drawings is of a familiar type which comprises work-holding means, stitch-forming mechanism including an upper thread-handling mechanism and an under thread-handling mechanism, and means to move 70 the work-holding means and stitch-forming mechanism relative to each other to effect the stitching operation around the edge of the buttonhole, said means operating to give the stitch-forming mechanism 75 and work-holding means a further movement at the end of the stitching operation to carry the work from stitching to buttonhole-cutting position. The work-holding means is of the usual type comprising a 80 clamp plate 1 on which the work is supported and clamping members 2 which are pivotally mounted on and movable toward and from the clamp plate 1 thereby to clamp the work in position or to release it. The 85 work is shown at 3 in Figs. 1 and 7, Fig. 1 showing the work clamped and Fig. 7 showing it unclamped. This clamp plate 1, with the clamping members 2 thereon, is removably mounted on the bed portion 4 90 of the frame 5 which supports the operative parts of the machine. The upper thread-handling mechanism is of the usual type comprising a needle 6 carried by a needle bar 7 which reciprocates in the head 8 of the frame. The under thread-handling 95 mechanism is carried by a turret 9 which is rotatably mounted in bearings 10 and 11 carried by the depending portion 12 of the frame. This under thread-handling 100 mechanism may have any known construction, but is herein illustrated as of the type shown in United States Patent No. 1,188,942, June 27, 1916, which includes a throat 15, an oscillatory needle for the under thread 105 (which is not illustrated herein), a looper 13 for taking the loops of upper thread as they are inserted through the work by the

needle 6, and a reciprocating actuating spindle 14 which is situated axially of the turret and by which the needle and looper of the under thread-handling mechanism are actuated and which in turn is given its reciprocations from an actuating lever 140. I have not attempted herein to illustrate all the constructional details of the under thread-handling mechanism as to do so 10 would tend to confuse the drawing and make the showing of the present invention somewhat obscure. Reference may be had, however, to the above-mentioned patent for further illustration of the under thread mechanism. Both the upper and the under thread-handling mechanism are mounted for rotation so as to effect the stitching around the ends of a buttonhole, and such rotation thereof is derived from a rock-shaft 16 15 which carries two segmental gears 17 and 18 that mesh with gears 19 and 20 carried by the upper thread-handling mechanism and under thread-handling mechanism, respectively. The rock-shaft 16 is oscillated from 20 the feed cam 21 in usual manner.

The work-holding means, comprising the clamp plate 1 and work clamps 2, and the stitch-forming mechanism have a movement relative to each other to provide for carrying 25 the stitching along the edges of the buttonhole and also to provide for carrying the work from stitching to buttonhole-cutting position as usual in sewing machines of this type. In the machine shown this 30 relative movement is provided for by so mounting the work-holding means that it can move back and forth on the bed plate 4. For this purpose the clamp plate 1 of the work-holding means is slidably mounted in 35 ways 22 on the bed plate 4, and it derives its reciprocating movement from the feed cam 21. Said cam is provided with a cam groove in which operates a projection 23 depending from a slide 24 that is mounted for reciprocating movement on the bed 4, said slide being detachably connected to the clamp plate 1 by means of a latch 25. The detachable connection between the clamp plate 1 and the latch 25 permits the clamp plate 40 with the work clamps thereon to be withdrawn or removed from the front of the bed plate.

26 is the usual cutter by which the buttonhole is cut. The parts thus far described 45 are or may be all as usual in buttonhole sewing machines of this type and hence it will not be necessary to further describe them. I will, however, briefly refer to the sequence of operations in the sewing of the 50 buttonhole.

When the machine is at rest the work clamps 2 are elevated, as shown in Fig. 7. The work 3 is then placed beneath the clamps and when the machine is set in operation, the clamps 2 are first carried down

into clamping position, as shown in Fig. 1, thus clamping the work to the clamp plate, and the cutter 26 is then operated to cut the buttonhole. After the buttonhole is cut, the work-holding means is moved toward 70 the right, Fig. 1, by the feed cam 21, thus to carry the work from buttonhole-cutting to stitching position, and when the work has been brought into stitching position, the stitching mechanism is set in operation. 75 The feed cam then continues moving the work-holding means so as to give the work a feeding movement to effect the formation of the edge stitches along one side of the buttonhole, and when the end of the buttonhole has been reached, the rock-shaft 16 is turned to cause the stitch-forming mechanism to swing around the end of the buttonhole. The feed cam then gives the work-holding means a reverse feeding movement 80 to provide for forming the stitches on the other side of the buttonhole, and when the stitching has been completed, the stitch-forming mechanism is brought to rest. 85 The feed cam, however, continues its movement and operates to bring the work-holding means from stitching to buttonhole-cutting position, after which the machine is brought to rest with the parts in the position shown in Fig. 1.

90 My present improvement relates to means for acting on the under thread at the end of the stitching operation on a buttonhole and while the work is being carried from stitching to buttonhole-cutting position for the 10 purpose of drawing out from the thread supply a sufficient length of under thread to insure the proper formation of the initial stitch on the next succeeding buttonhole, and then to cut the under thread close to 105 the work. The device herein illustrated for this purpose comprises a pull-off member 27 which is situated to act on the under thread between the work 3 and the clamp plate 1. This pull-off member 27 is in the form of a 110 finger which extends from a slide 29 mounted on a clamp plate 1 and which has a thread-receiving notch 28 in the end thereof. The slide 29 is mounted to slide in ways 30 formed in the plate 1, and the finger 27 115 lies closely adjacent to the plate 1 and beneath the work 3. Means are provided for moving the plate 29 toward the left, Fig. 5, at the end of the stitching operation thereby to cause the notch 28 in the finger to engage the under thread beneath the work thereby to draw out from the source of supply a suitable length of under thread. The means by which this movement is given to the slide 29 is rendered operative by the 125 movement of the clamp plate 1 by which the work is carried from stitching to buttonhole-cutting position at the end of the stitching operation. The clamp plate 1 carries a pivotal stud 31 on which is pivotally 130

mounted a lever 32 that is connected at one end to a link 33 which in turn is pivoted at 34 to the slide 29. The end 35 of the lever 32 is adapted to have engagement with an 5 abutment shoulder 36 fixed to the bed plate 4, said shoulder 36 thus being stationary. The end 35 of the lever 32 has connected thereto one end of a pulling spring 37, the other end of said spring being fastened to 10 an arm 38 that is secured to the clamp plate 1. During the stitching operation on the buttonhole, the slide 29 will be in the position shown in Fig. 5, in which position the notched finger 27 is situated considerably 15 in advance of the stitching point, and the lever 32 will be so situated that the end 35 thereof is in line with the fixed abutment 36 so that the movement of the clamp plate toward the left, Fig. 5, will bring said end 20 35 of the lever against the abutment. After the stitching on a buttonhole has been completed and the stitch-forming mechanism has been brought to rest, the clamp plate 1 is moved from the position shown in Fig. 25 5 to that shown in Figs. 6 and 7 thereby to carry the work from stitching to buttonhole-cutting position. During this movement of the clamp plate the end 35 of the lever 32 is resting against the fixed abutment 36, and 30 as the stud 31 is fixed to the clamp plate, the central portion of the lever 32 will be moved forwardly with the clamp plate. Since the end 35 of the lever engages the 35 fixed abutment this will cause the opposite end of the lever which is pivoted to the link 33 to move forwardly at a much greater speed than that at which the clamp plate 1 moves. As a result, the slide 29 is moved forwardly on the clamp plate 1, such forward movement carrying the finger 27 forwardly beneath the work so as to bring the notch thereof into engagement with the under thread. The movement of the slide is sufficient to cause the notched finger to draw 40 off from the throat 15 a length of under thread shown at 39 in Fig. 7. The clamps 2 are released and elevated by the usual means just before the clamp plate moves to carry the work from stitching to buttonhole cutting position so that they do not interfere with this pulling-off movement of the finger 27.

The finger 27 has associated therewith means for cutting the under thread after 55 the desired length 39 has been drawn off therefrom and the length 39 which is thus drawn off is sufficient so that when the stitching begins on the next succeeding buttonhole the extra length 39 will provide for 60 the proper formation of the initial stitch on the buttonhole without danger that the end of the thread will be drawn through the goods. By thus properly gaging the amount of thread 39 which is drawn from the throat 65 15 at the completion of the stitching on each

buttonhole, it is possible to insure that the initial stitch of each buttonhole will be properly formed without the necessity of providing means for holding the under thread to prevent it from being pulled through the 70 goods.

The thread-cutting mechanism herein illustrated is in the form of shears comprising two shearing blades 40 and 41 which are pivotally mounted on the stud 42 carried by 75 the slide 29. The upper shearing blade 41 has a notch 43 formed in the end thereof and the lower shearing blade 40 is provided with a shearing edge 44. The shearing blades are normally in the relative position shown in 80 Fig. 5, thus providing a notch in alinement with the notch 28 into which the under thread is received. Means are provided for swinging the shearing blades relative to each other on the stud 42 during the final 85 forward movement of the slide 29, thereby causing them to sever the under thread just when the desired length 39 thereof has been pulled from the throat 15. To accomplish this I have provided each of the shearing 90 blades with depending pins, the pin depending from the upper shearing blade 41 being indicated at 45 and that depending from the lower shearing blade 40 being indicated at 46. These pins operate in slots 47 and 48 95 formed in a cam plate 49 which is secured to the bed plate 4. The slots or grooves 47, 48 are straight and parallel for the greater portion of their length and at their inner ends they diverge, as shown at 50. So long 100 as the pins 45 and 46 are traveling in the straight portions of the grooves, the shearing blades will be held in the relative position shown in Fig. 5, but when the pins enter the diverging portions 50 of the 105 grooves, then the blades will be turned relative to each other, thus cutting the thread beneath the work. This cutting operation of the thread thus takes place during the final movement of the clamp plate 1. It 110 will be observed that the under thread is cut close to the work and that the severing of the thread does not occur until after the required length 39 has been drawn from the 115 throat 15.

As soon as the under thread has thus been severed and before the machine comes finally to rest, the slide 29 is returned to the initial position shown in Fig. 5, thus withdrawing the pulling-off finger 27 and the shears from beneath the work. To accomplish this I have provided the link 33 with a depending pin 51 which operates in a space or wide groove 52 formed in the cam plate 49. This groove 52 is provided at one end 120 with an inclined cam surface 53 and at the other end with another inclined cam surface 54. When the lever 32 is in the position shown in Fig. 5 with the end 35 thereof against the abutment 36, the pin 51 will be 125 130

lying against the outer side 55 of the groove 52. As the clamp plate 1 moves forwardly to carry the work from stitching to button-hole-cutting position the pin 51 will be 5 brought into engagement with the cam face 53, and as the pin rides down this cam face, the link 33 will be swung about its pivot 34, thereby moving the lever 32 longitudinally, said lever being provided with the slot 36 10 through which the pivotal stud 31 extends to permit of such movement, and the end 35 of the lever will thus be forced off from the abutment 36, as seen in full lines Fig. 6. As soon as this occurs, the spring 37 will 15 contract, thus swinging the lever 32 into the dotted line position, Fig. 6, such movement operating to give the slide 29 a retracting or backward movement and withdrawing the finger and shears from the thread. The 20 cam surface 53 is so designed that this disengagement of the lever from the abutment face 36 occurs just after the thread has been severed. When the machine is set in operation again and the clamp plate 1 is moved 25 toward the right, the end 35 of the lever is carried beyond the abutment 36 and the pin 51 is brought against the cam surface 54 thereby moving the lever 32 longitudinally and placing the end 35 thereof in line with 30 the abutment 36 so that on the next forward movement of the clamp plate said end will be brought into engagement with the abutment, as shown in Fig. 5.

The turret 9 is provided with the usual 35 disk tension device 57 through which the under thread μ is led before it is delivered to the under needle. In order to permit the extra length 39 of under thread to be freely drawn off without danger of breaking the 40 thread, it is desirable that the tension on the under thread should be released during the drawing-off movement. I have, therefore, provided herein means for releasing the friction of the tension device 57 on the under 45 thread while said under thread is being acted upon by the pulling-off finger 27. For this purpose I have provided a finger 58 having a wedge-shaped end 59 which is adapted to be forced between the tension disks 57 at 50 the desired time thereby to separate them. This finger 58 is shown as secured to a lever 60 which is pivoted to the turret at 61, said lever being suitably guided in a guide member 62. Means are provided for raising the 55 lever 60 about its pivot 61 at the time that the pulling-off finger 27 is acting on the under thread. The device I have herein provided for this purpose comprises an elbow-lever 63 which is pivoted at 64 to the 60 portion 12 of the frame and one arm of which has a depending extension 65 provided with a laterally-extending flange 66. The other arm of the lever 63 has a link 67 pivotally connected thereto which link ex- 65 tends through a bracket 68 secured to the slide 24. The link 67 is provided with an adjustable collar 69 and a spring 70 encircles the link 67 and is confined between the collar and the portion of the bracket through which the link 67 extends. The 70 slide 24 has a movement to the left Fig. 1, while it is moving the work from stitching to buttonhole-cutting position, and the construction of the lever 63 and link 67 is such that just as the pulling-off finger 27 is about to act on the thread the bracket 68 comes against the spring 70 so that during further movement of the slide 10, the bracket is acting through the spring 70 and link 67 to turn the elbow-lever 63 about its pivot thereby raising the flange 66. In sewing machines of this type, the turret 9 is given a rotative movement during and after the stitching operation, and the parts are so designed that when the stitch-forming mechanism has been brought to rest at the end of a buttonhole and the clamp plate 1 is being moved to carry the work from stitching to buttonhole-cutting position, the turret 9 will be positioned so that the outer end 80 of the lever 60 will be directly above the flange 66. Consequently, when the lever 63 is operated to raise the flange 66, such flange will engage the end of the lever 60 and force the wedge 59 between the tension disks 57 85 and separate the latter, thereby to release the tension on the under thread. This operation occurs just at the time that the pulling-off finger 27 is acting on the under thread to draw off the length 39, as above described. 90

In many sewing machines of the type herein shown, it is customary to employ means for delivering a stay-cord to the edge of the buttonhole as the stitches are formed so that the edge stitches of the buttonhole 105 are concatenated about the stay-cord. The machine herein shown is of this type and the thread-cutting means above described are adapted to cut the stay-cord as well as the under thread. This stay-cord is shown 110 at 71 and it passes between two friction disks 72 and thence to the throat 15. The stay-cord is delivered from the throat-plate close to the under thread μ and hence is engaged by the notch 28 of the pulling-off 115 finger 27 when the latter is used to draw off the length of under thread. In the operation of stitching the buttonhole, however, the stay-cord is merely laid along the edge of the buttonhole, and when the stitching operation 120 begins on any buttonhole, it is desirable to have only a sufficient length of the stay-cord extending from the throat to overlie the portion of the buttonhole edge where the first stitches are being formed. I have, 125 therefore, provided means herein whereby after the stay-cord has been drawn out from the throat and cut the surplus length of the stay-cord which projects beyond the throat will be drawn back so as to leave only 130

the proper projecting length to insure the proper formation of the buttonhole without leaving a projecting end of the stay-cord. To accomplish this I employ an arm 74 which is pivotally mounted on the turret at 73 and is provided with an aperture 75 through which the stay-cord passes before it is led to the throat. The arm 74 is backed by a light spring 76 which urges it toward the full line position Fig. 4. During the sewing operation the tension on the stay-cord is sufficient to compress the spring 76 and to hold the arm in the dotted line position Fig. 4. When at the end of the stitching operation the slide 29 and the pulling-off finger 27 are moved forwardly into the position shown in Fig. 7, the notch 28 of said finger engages both the under thread *u* and the stay-cord 71 between the throat 15 and the work and operates to draw off a suitable length of both the under thread and stay-cord, as above described. The stay-cord as well as the under thread is thus received in the notch formed by the cutting blades of the shears, and when the shears are actuated at the end of the forward movement of the slide 29, they operate to cut the stay-cord as well as the under thread. As soon as the stay-cord is cut, then the resiliency of the spring 76 moves the arm 74 from the dotted to the full line position Fig. 4, such movement of the arm withdrawing from the throat 15 a certain amount of the extra length of the stay-cord which has been pulled off by the finger 27. The movement of the arm 74 due to the spring 76 is limited by a stop member 77 which is situated to grip the stay-cord between it and the arm. This stop member 77 thus acts not only to limit the swinging movement of the arm, but also to prevent the stay-cord from being pulled backwardly.

When the sewing machine has been brought to rest, therefore, a certain length 39 of the under thread and a lesser length of the stay-cord will be found projecting from the throat 15. When the initial stitch on any buttonhole is formed the under thread is held in the fabric by its friction with the goods, and although there is, of course, a tendency when the first stitch is set to pull the end of the under thread through the goods, yet the length 39 together with the friction between the thread and the goods is sufficient to prevent this from occurring so that the first stitch is properly made. The stay-cord is merely laid against the edge of the buttonhole during the stitching operation and the stitches are formed over the cord, thus binding it in place, and the length of the stay-cord which is left projecting from the throat by the movement of the arm 74 from the dotted to the full line position is just sufficient to insure the proper formation of the buttonhole

without leaving any projecting end of stay-cord which requires to be trimmed after the buttonhole is finished. With my machine, therefore, both the under thread and stay-cord are cut in such a way that no projecting ends are left and no trimming of the buttonhole is necessary. 70

In sewing machines of this type the stitch-forming mechanism is usually brought to rest with the upper needle 6 raised and with the upper thread extending from the needle down through the work and around the looper and back to the work again. This loop of upper thread will be engaged in the slot 28 with the under thread and stay-cord 75 80 and will be severed by the shears and thus all threads on the under side of the work are sheared closely to the work when the button-hole is completed.

It is customary to provide sewing machines of this type with a device for cutting the upper thread above the work, but I have not herein illustrated such a device as it forms no part of the present invention and to do so would only tend to confuse the drawings. I would state, however, that where such a thread cutter is used for cutting the upper thread between the needle and the work, it will preferably be constructed to be operated just before the pulling-off finger is moved forwardly to draw off the under thread, so that when the pulling-off finger does operate the work will not be tied down to the clamp plate by the loop of upper thread which extends around the 90 95 looper. 100

While I have illustrated herein a selected embodiment of my invention, I do not wish to be limited to the constructional features shown. 105

I claim:

1. In a sewing machine, the combination with a frame, of work-clamping means removably sustained thereon, stitch-forming mechanism comprising upper thread-handling mechanism and under thread-handling mechanism, and means operative at the end of a stitching operation to act on the under thread beneath the work and draw out from the source of supply a sufficient length 110 115 to insure the proper formation of the initial stitch of the next succeeding stitching operation without the necessity of holding said severed end, said means being carried by and removable from the frame with the 120 work-clamping means.

2. In a sewing machine, the combination with a frame, of work-clamping means removably mounted thereon, stitch-forming mechanism comprising upper thread-handling mechanism, and under thread-handling mechanism, and means carried by the removable work-clamping means and operative at the end of a stitching operation to act on the under thread beneath the work 125 130

and draw out from the source of supply a sufficient length to insure the proper formation of the initial stitch of the next succeeding stitching operation without the necessity 5 of holding said severed end and then to cut the under thread close to the work.

3. In a sewing machine, the combination with work-holding means, of stitch-forming mechanism comprising means for manipulating both an upper and an under thread, means for giving the work-holding means and stitch-forming mechanism a relative movement during the stitching operation and a further relative movement at the end 10 of the stitching operation by which the work and stitch-forming mechanism are moved relatively from stitching to buttonhole cutting position, and a device operative during such further relative movement to act on the 15 under thread beneath the work without gripping said thread thereby to draw out a sufficient length thereof to insure the proper formation of the first stitch of the next succeeding buttonhole without the necessity of holding said under thread.

4. In a sewing machine, the combination with work-holding means, of stitch-forming mechanism comprising means for manipulating both an upper and an under thread, means for giving the work-holding means and stitch-forming mechanism a relative movement during the stitching operation and a further relative movement at the end 20 of the stitching operation by which the work and stitch-forming mechanism are moved relatively from stitching to buttonhole-cutting position, and means operative during such further relative movement to act on the under thread beneath the work there- 25 by to draw out a sufficient length thereof to insure the proper formation of the first stitch of the next succeeding buttonhole without the necessity of holding said under thread and then to cut the thread close to the work after said length has been drawn out.

5. In a sewing machine, the combination with a frame, of work-holding means removably mounted thereon and comprising two clamping members between which the work is held, stitch-forming mechanism comprising means for manipulating both an upper and an under thread, and means carried by the work-holding means and operative at the end of the stitching operation to act on the under thread between the clamping members and beneath the work thereby to draw out a length of under thread sufficient to insure the proper formation of the 50 initial stitch of the next stitching operation.

6. In a sewing machine, the combination with a frame, of work-holding means removably mounted thereon and comprising two clamping members between which the work 55 is held, stitch-forming mechanism comprising

means for manipulating both an upper and an under thread, and means carried by the removable work-holding means and operative at the end of the stitching operation to act on the under thread between 70 the clamping members and beneath the work thereby to draw out a length of under thread sufficient to insure the proper formation of the initial stitch of the next stitching operation and then to cut the thread close 75 to the work.

7. In a sewing machine, the combination of a frame, work-holding means removably mounted thereon, under thread-handling mechanism, a rotary turret on which said 80 mechanism is sustained, a tension for the under thread mounted on said turret, means carried by the removable work-holding means and operative at the end of a stitching operation to act on the under thread beneath the work and draw through said tension device a length of thread sufficient to insure the proper formation of the initial stitch of the next succeeding operation.

8. A sewing machine such as set forth in 85 claim 7, in combination with means to release the tension for the under thread while said length of under thread is being drawn off.

9. In a buttonhole sewing machine, the 90 combination of stitch-forming mechanism including means for manipulating both an upper and an under thread, work-holding means, means to move said work-holding means and stitch-forming mechanism relative to each other both during the stitching operation on a buttonhole and subsequent thereto, thereby to carry the work from stitching to buttonhole-cutting position, a pulling-off member movably mounted on 100 the work-holding means, and means to actuate said member at the end of the stitching operation to pull off a length of under thread sufficient to insure the proper formation of the initial stitch on the next buttonhole.

10. In a buttonhole sewing machine, the combination of stitch-forming mechanism for concatenating both upper and under threads, work-holding means, a slide on the 105 work-holding means having a pulling-off finger, and means to move the slide at the end of a stitching operation on the buttonhole to cause said finger to engage the under thread and pull off a length thereof.

11. A buttonhole sewing machine as set forth in claim 10 in combination with shears carried by the slide and means to actuate the same to cut the under thread close to the work.

12. In a buttonhole sewing machine, the combination with stitch-forming mechanism including means for manipulating both an upper and an under thread, of work-holding means including a clamp plate, means to 115

- move the clamp plate and stitch-forming mechanism relative to each other at the end of a stitching operation, a slide carried by said clamp plate and provided with a pulling-off finger, a lever pivoted to said clamp-plate and connected to the slide, and a fixed abutment against which one end of the lever has engagement whereby the movement of the clamp plate will project the finger into position to draw off a length of under thread.
13. A buttonhole sewing machine as set forth in claim 12 in combination with means to release the lever from said abutment when the length of under thread has been pulled off, and means to return said slide to its normal position.
14. In a buttonhole sewing machine, the combination of stitch-forming mechanism including means for manipulating both an upper and an under thread, work-holding means including a clamp plate, means to move the work-holding means relative to the stitch-forming mechanism at the completion of the stitching operation on a buttonhole, a slide on the work-holding means having a pulling-off finger, means to move the slide at the end of the stitching operation to cause said finger to engage the under thread and draw off a length thereof, shears also carried by the slide, and a stationary cam plate co-operating with said shears to actuate them as the slide is moved.
15. In a buttonhole sewing machine, the combination of stitch-forming mechanism including means for manipulating both an upper and an under thread, work-holding means including a clamp plate, means to move the work-holding means relative to the stitch-forming mechanism at the completion of the stitching operation on a buttonhole, a slide on the work-holding means having a pulling-off finger, means to move the slide at the end of the stitching operation to cause said finger to engage the under thread and draw off a length thereof, a pair of shearing blades carried by the slide, each having a projection and a stationary cam plate having cam grooves in which said projections are received whereby movement of the slide actuates the shears to cut the under thread.
16. In a buttonhole sewing machine, the combination of work-holding means, a rotatable turret, stitch-forming mechanism including under thread mechanism carried by said turret, a tension for the under thread also carried by the turret, a tension-releasing member mounted on the turret, means to draw out a length of under thread at the end of the stitching operation, and means to actuate said tension-releasing member to release the tension while said length is being drawn out.
17. In a buttonhole sewing machine, the combination of work-holding means, a rotatable turret, stitch-forming mechanism including under thread mechanism carried by said turret, a tension for the under thread also carried by the turret, a tension-releasing member mounted on the turret, means to draw out a length of under thread at the end of the stitching operation, and other means also actuated by said relative movement to actuate the tension-releasing member while the thread is being thus drawn out.
18. In a buttonhole sewing machine, the combination of work-holding means, of a rotatable turret provided with a throat and having provision for delivering a stay-cord from the throat, under thread mechanism carried by the turret, and means operative at the end of a stitching operation to act on the under thread and the stay-cord and draw out from the throat different lengths thereof.
19. In a buttonhole sewing machine, the combination of work-holding means, a rotatable turret provided with a throat and having provisions for delivering a stay-cord therefrom, under thread mechanism carried by said turret, and means carried by the work-holding means to engage the under thread and the stay-cord at the end of the stitching operation and draw from the throat a length of each.
20. A buttonhole sewing machine such as set forth in claim 19; in combination with means to retract part of the length of the stay-cord which is thus drawn from the throat.
21. A sewing machine such as set forth in claims 19 and 20 in which the means to retract part of the stay-cord is carried by the turret.
22. A buttonhole sewing machine, such as specified in claim 19, in combination with a spring-pressed finger pivoted to the turret and having a stay-cord-receiving aperture through which the stay-cord passes.
23. In a buttonhole sewing machine, the combination of work-holding means, a rotatable turret provided with a throat and having provision for delivering a stay-cord therefrom, under thread mechanism carried by the turret, means operative at the end of a stitching operation on a buttonhole to act on the under thread and stay-cord thereby to draw a length of each from the throat, a tension device for the stay-cord, an arm pivoted to the turret and having a guiding aperture through which the stay-cord passes between the tension device and the throat, and a comparatively-light spring acting on said arm and tending to urge it away from the throat, said spring having a less resistance than the tension.

24. In a buttonhole sewing machine, the combination of work-holding means, a rotatable turret provided with a throat and having provision for delivering a stay-cord 5 therefrom, under thread mechanism carried by the turret, means operative at the end of a stitching operation on a buttonhole to act on the under thread and stay-cord thereby to draw a length of each from the throat, 10 a tension device for the stay-cord, an arm pivoted to the turret and having a guiding aperture through which the stay-cord passes between the tension device and the throat, a comparatively-light spring acting on said 15 arm and tending to urge it away from the throat, said spring having a less resistance than the tension, and means coöperating with said arm to prevent backward movement of the stay-cord.
- 20 25. In a sewing machine, the combination with a frame of stitch-forming mechanism for concatenating both upper and under threads, work-holding means removably carried by said frame, a slide on the work-holding means, thread-cutting devices carried by said slide, and automatic means to move the slide at the end of a stitching operation to cause said thread-cutting devices to engage and cut the thread between 30 the work and the work-holding means.
26. In a sewing machine, the combination with stitch-forming mechanism, of work-holding means, means to produce a relative movement between the stitch-forming mechanism and work-holding means thereby to feed the work, a slide on the work-holding means, thread-cutting shears carried by the slide, means operative automatically to move the slide at the end of a stitching operation in 35 the direction of feed thereby to carry the shears into position to cut the under thread beneath the work, and means to actuate the shears.
27. In a sewing machine, the combination with stitch-forming mechanism, of work-holding means, means to produce a relative movement between the stitch-forming mechanism and work-holding means thereby to feed the work, a slide on the work-holding 40 means, thread-cutting shears carried by the slide, means operative automatically to move the slide at the end of a stitching operation in the direction of the feeding movement to carry the shears into position to cut the under thread beneath the work, and means to operate the shears by the movement of the slide.
28. In a sewing machine, the combination with stitch-forming mechanism, of work-holding means, means to give the work-holding means a feeding movement, a slide on the work-holding means, thread-cutting shears carried by the slide, automatic means to move the slide at the end of a stitching 45 operation in the direction of the feeding
- movement thereby to carry the shears into position to cut the under thread beneath the work, and a stationary cam plate coöperating with said shears to actuate them as the slide is moved. 50
29. In a sewing machine, the combination with stitch-forming mechanism, of work-holding means, a slide on the work-holding means having a pulling-off finger, means to move the slide at the end of a stitching operation to cause the finger to engage the under thread and draw off a length thereof, 55 shears also carried by said slide, and a stationary cam plate coöperating with said shears to actuate them as the slide is moved. 60
30. In a sewing machine, the combination with work-holding means, of under-thread-handling mechanism, a rotary turret on which said mechanism is sustained, a tension for the under-thread mounted on said 65 turret, means operative at the end of a stitching operation to act on the under-thread beneath the work and draw through said tension device a length of thread sufficient to insure the proper formation of the initial stitch of the next succeeding sewing operation, and means to release the tension for the under-thread while said length of under thread is being drawn off. 70
31. In a buttonhole sewing machine, the combination with a frame, of work-holding means removably sustained thereon, stitch-forming mechanism, means to produce a relative movement between the stitch-forming mechanism and work-holding means 75 during the stitching on a buttonhole, and a further relative movement at the completion of the stitching operation, and means carried by the removable work-holding means and operative during such further 80 relative movement to draw out from the source of supply a sufficient length of under-thread to insure the proper formation of the initial stitch of the next succeeding 85 stitching operation.
32. In a buttonhole sewing machine, the combination with a frame, of work-holding means removably sustained thereon, stitch-forming mechanism, means to produce a relative movement between the stitch-forming mechanism and work-holding means during the stitching on a buttonhole, and a further relative movement at the completion of the stitching operation, and means carried by the removable work-holding 90 means and operative during such further relative movement to draw out from the source of supply a sufficient length of under-thread to insure the proper formation of the initial stitch of the next succeeding 95 stitching operation and then to cut the under-thread close to the work. 100
33. In a sewing machine, the combination with a frame having a bed plate, of work-holding means sustained by the bed plate 105

and capable of ready removal therefrom, stitch-forming mechanism comprising means to concatenate an upper and an under thread, a thread-cutting device carried by 5 and removable from the bed plate with the work-holding means, and means operative automatically at the end of the stitching operation to move the thread-cutting device and work-holding means bodily relative to 10 each other thereby to bring said device into thread-cutting position and then to actuate said device to cut the thread.

34. In a sewing machine, the combination with a frame having a bed plate portion 15 provided with open-ended ways, of a clamp plate slidably mounted in said ways and removable from the bed plate through the open ends thereof, work clamps for clamping the work on the clamp plate, stitch- 20 forming mechanism comprising means for concatenating an upper and an under thread, a thread-cutting device carried entirely by the clamp plate and situated normally out of thread-cutting position, and 25 means operative automatically at the end of the stitching operation to produce a relative movement between the thread-cutting device and the clamp plate thereby to bring said device into thread-cutting position and 30 then to actuate said device to cut the thread.

35. In a buttonhole sewing machine, the combination with a frame having a bed plate portion provided with open-ended ways, of a clamp plate slidably mounted in 35 said ways and removable through the open end thereof, stitch-forming mechanism, means to give the stitch-forming mechanism and clamp plate a relative movement during the stitching of a buttonhole and a further relative movement at the end of a 40 stitching operation, a thread-cutting device carried by the clamp plate, and means operative during such further relative movement to move the thread-cutting device bodily on the clamp plate thereby to bring it 45 into thread-cutting position and then to actuate said device to cut the under thread.

36. In a sewing machine, the combination with a frame having a bed plate portion 50 provided with open-ended ways, of work-holding means slidably mounted in said ways and removable from the bed plate

through the open end of said ways, a thread-cutting device movably carried on the work-holding means and removable from the 55 frame therewith, and means to move said thread-cutting device bodily relative to the work-holding means thereby to place it in thread-cutting position and then to actuate said device to cut the thread.

37. In a sewing machine, the combination with a frame, of work-holding means removably sustained thereby and comprising a clamp plate on which the work is sustained, and work clamps for clamping the 60 work thereto, a thread-cutting device movably carried on the work-holding means, and means to move said device bodily relative to the work-holding means, thereby to place it in thread cutting position and then to actuate said device to cut the thread.

38. In a sewing machine, the combination with a frame, of work-holding means removably sustained thereby, means to form a series of short seams and to lay a stay- 75 cord along each seam as it is formed, a stay-cord cutting device carried by the work-holding means, and means operative at the end of each seam to move said device bodily on the work-holding means thereby to bring 80 it into stay-cord-cutting position and then to actuate said device to cut the stay-cord.

39. In a sewing machine, the combination with stitch-forming mechanism, of work-holding means, a slide on the work-holding 85 means, thread-cutting shears carried by the slide, means operative automatically to move the slide at the end of a stitching operation to carry the shears into position to cut the under thread beneath the work, and means 90 to actuate the shears.

40. In a sewing machine, the combination with stitch-forming mechanism, of work-holding means, a slide on the work-holding means, thread-cutting shears carried by the 95 slide, means operative automatically to move the slide at the end of a stitching operation to carry the shears into position to cut the under thread beneath the work, and means to operate the shears by the movement of 100 the slide.

In testimony whereof I have signed my name to this specification.

CHRISTIAN H. T. HAGELSTEIN
